UNITED STATES PATENT OFFICE.

ISAAC H. ROHRER, OF LOS ANGELES, CALIFORNIA.

GREASE-CUP.

1,198,960.

Specification of Letters Patent. Patented Sept. 19, 1916.

Application filed May 23, 1916. Serial No. 99,402.

To all whom it may concern:

Be it known that I, ISAAC H. ROHRER, a citizen of the United States, residing at Los Angeles, in the county of Los Angeles and State of California, have invented new and useful Improvements in Grease-Cups, of which the following is a specification.

My invention relates to improvements in grease-cups in which a cap is screwed over a body-member for the reception of lubricant, which may be squeezed or injected into a bearing by the movable interengaging of the cap and the body; and the objects of my improvements are, to simplify the filling of grease-cups by eliminating the unscrewing and fitting together of the threaded interengaging of the cap and the body; to provide a cylindrical casing, screwed over the body of the device, with an open upper end to make the refilling possible from the upper end of the device; to provide the lower end of the casing with a shoulder preventing the casing from being unscrewed; to provide interlocking means near the upper edge of the casing; to provide a cap to close the upper open end of the casing having suitable cut-outs or recesses to engage with the interlocking means on the casing; the invention consisting in the construction, combination and arrangement of devices hereafter more fully described and claimed, and illustrated in the accompanying drawing, in which—

Figure 1 is a vertical cross section through the device. Fig. 2 is a side view of the cap. Fig. 3 is a slightly modified construction of the cap in cross section. Fig. 4 is a section on line 4—4 of Fig. 3.

Similar numbers refer to similar parts throughout the papers.

The body 1 of the device is provided on the upper end with a short cylindrical part 2, threaded on the outside. A casing 3, threaded on the inside fits turnably on the threaded end of the body having a shoulder 4 on the lower end preventing the casing from being unscrewed in upward direction.

It will be understood that the device is placed on top of or near a bearing so that

it may supply the latter with lubricant, and the casing 3 of my device cannot be unscrewed in downwardly direction as the device is normally too close to the bearing to allow a shifting to such an extent. The threads on a grease-cup are usually rather loosely fitting, and, after re-filling the cup, it very often happens that the threads do not catch right and very soon are spoiled. A main feature of my device is to eliminate this trouble of ruining the threads by constructing my device so that it can easily be re-filled without having to unscrew it.

Near the upper end of the casing 3 I provide projections or pins 5 as a locking means. The cap 6 fits over the casing 3 having cut-outs 7 to engage with the locking means on the casing, see Fig. 2. In Figs. 3 and 4, a slightly modified construction of the cap is shown having suitably formed recesses 8 instead of the cut-outs 7, shown in Fig. 2.

Disengaging the cutouts or recesses of the cap 6 from the projections or pins 5 of the casing 3, the device can be re-filled from the top, and, after the re-filling the cap is engaged again as before, making cap 6 and casing 3 one member to be screwed in the same manner as other well-known grease-cups. To make the upper end of the device tight, a gasket 9 is placed between the cap 6 and the casing 3.

Having thus described my invention, I claim:

1. A grease-cup consisting of a body-member, a casing movably engaging with the body member having locking means near the upper open end of the casing, and a cap fitting over the upper end of the casing engaging with the locking means.

2. A grease-cup consisting of a body-member having a threaded cylindrical upper end, a casing turnably fitting with the lower end on the threaded upper end of the body-member having a projection near the upper end, and a cap fitting over the upper end of the casing engaging with the projection on the casing.

3. A grease-cup consisting of a body-member having a cylindrical upper end

threaded on the outside, a casing turnably fitting with its lower end on the threaded upper end of the body-member having a locking means near the upper end of the casing, a shoulder formed on the lower end of the said casing engaging with the body-member adapted to prevent the casing from unscrewing, and a cap fitting over the upper

end of the casing engaging with the locking means on the casing.

10

In testimony whereof I hereunto affix my signature in the presence of two witnesses.

ISAAC H. ROHRER.
